UNITED STATES PATENT OFFICE

BERNARD STANLEY MAHER, OF OAKLAND, CALIFORNIA

COMPRESSION EXPLOSION ENGINE

Application filed July 7, 1930. Serial No. 466,314.

My invention relates to improvements in compression explosion engines, and it consists in the combinations, constructions and arrangements hereinafter described and claimed.

An object of my invention is to provide a compression explosion engine that is designed to impart more than one power impulse to the power piston during the firing stroke of the piston. In my co-pending application Serial No. 408,043, filed Nov. 18, 1929, on an engine, I showed spark plugs for igniting the gas at the proper moment. In the present invention I show atomizers for straying a liquid fuel into the engine at the proper moments. The chambers for receiving the air and gas are made low fitting in height so as to obtain the desired compression for igniting the fuel.

Other objects and advantages will appear as the specification proceeds, and the novel features of the device will be particularly pointed out in the claims hereto annexed.

My invention is illustrated in the accompanying drawings, in which:

Fig. 1 is a transverse section through the device,

Figure 2 is a section along the line 2—2 of Figure 1, and

Figures 3 and 4 are sectional views through a novel type of valve used in the device.

In carrying out my invention, I provide an engine block indicated generally at 1, this block having a power cylinder 2 and a pump cylinder 3. A power piston 4 is mounted in the cylinder 2, and a pump piston 5 is mounted in the cylinder 3. Connecting rods 6 and 7 extend from the pistons 4 and 5 respectively and are radially connected at 8 and 9 to gears 10 and 11. I have shown the connection 8 as being disposed substantially midway between the periphery of the gear 10 and its center, although this connection may be disposed near the rim of the gear if desired without departing from the spirit and scope of the invention. This would lengthen the stroke of the piston 4, and the cylinder 2 would also have to be lengthened to take care of this increased stroke.

The ratio of the gears 10 and 11 is such

as to cause the piston 5 to move twice as fast as the piston 4. It is obvious that this ratio may be changed as desired by substituting different combinations of gears. The gear 10 meshes with an idler gear 12 mounted upon a shaft 13 while the idler gear meshes with a gear 14 mounted upon the driven shaft 15. All of the gears are disposed within a crank-case 16 (see Figure 1).

A partition 17 extends across the cylinder 3 and provides a compartment 18, so forming the firing-head 19. An air intake valve 20 places an air intake manifold 21 in communication with the cylinder 3. A check valve 22 places the cylinder 3 in communication with the compartment 18. It should be noted that the head of the valve lies flush with the top of the partition 17. An atomizing fuel injector 23 is designed to deliver fuel to the compartment 18 at the proper instant. A valve indicated generally at 24 and hereinafter described more in detail places the compartment 18 in communication with the top of the cylinder 2.

A fuel injector and atomizer 25 similar to the atomizer 23 is placed in the top of the cylinder 2. Figure 1 shows an exhaust valve 26 carried by the piston 4, this valve having a stem 27 that is designed to strike a perforated partition 28 for opening the valve 26 when the piston 4 nears the bottom of its stroke and after a casing 29 housing the valve 26 is received in an exhaust pipe 30 as shown by the dotted lines. Reference to Figure 2 shows the exhaust pipe 30 as leading exteriorly of the crankcase 16 and as being connected to an exhauster 31 driven by any means, not shown. A check valve 32 is disposed in the exhaust pipe 30.

Figures 3 and 4 show the valve 24 in detail. It will be noted that a valve plug 33 normally seats on a ring valve 34 and is yieldingly held in this position by a spring 35. The ring valve 34 carries guide rods 36, and these rods are connected to the ring 37 which presses against a spring 38. The rods 36 are slidably carried by sleeves 39, while the rod of the valve 33 is pinned to the sleeve 40. The sleeves 39 and 40 are integrally connected by means of a webbing. Figure 4 shows the

sleeves 39 moved until they contact with the ring valve 34, whereupon added pressure of the gases flowing through the valve will cause the ring valve 34 to open.

5 The engine is designed to work under the four-cycle principle or under the two-cycle principle. When the engine is working under the four-cycle principle, more than two charges are compressed in the chamber 18 before the spring 35 will permit the valve plug 33 to open in the manner shown in 10 Figure 4. This will permit the charge to move from the chamber 18 into the top of the cylinder 2. When an explosion takes 15 place in the chamber 18, the plug 33 and the ring valve 34 will both open and permit the exploding gas to move quickly from the chamber 18 into the top of the cylinder 2 in order to add another power impulse to the 20 piston 4 on its downward movement.

It should be noted that the gear 11 is mounted upon a stub shaft 40 and the gear 10 is mounted upon a stub shaft 41.

From the foregoing description of the 25 various parts of the device, the operation thereof may be readily understood.

The pump piston 5 draws air into the cylinder 3 through the valve 20. The air is compressed and delivered into the chamber 18, thence into the cylinder 2 by a valve 24. The piston 4 compresses the air charge up to the firing point, whereupon the atomizer 25 injects the fuel which is ignited by the heat of compression of the compressed air.

35 Slightly before the piston 4 reaches its midpoint position, another compressed air charge has been delivered into the chamber 18 and retained there. When the piston 4 reaches the midpoint position, the atomizer 23 injects a fuel charge and this is ignited by the heat of compression of the compressed air charge in the chamber 18. It is noted that the high compression temperature of the air charges delivered into the explosion spaces 45 is obtained by making the explosion spaces low fitting in height.

Cycle of operations for two-cycle arrangement

50 An air charge has already been placed in the top of the cylinder 2 and the piston 4 is at the top of its stroke. The piston 5 is at the bottom of its stroke. All of the valves are closed. A charge has also been drawn 55 into the cylinder 3.

At this phase of the operation, the atomizer 25 injects fuel which is ignited by the temperature of the compressed air charge, thus driving the piston 4 downwardly. Slightly 60 before the piston 4 has reached the midpoint of its downward movement, the piston 5 will have compressed the air in the cylinder 3 and will have delivered this compressed air into the chamber 18 past the check valve 22. 65 At the instant the piston 4 reaches the mid-

point of its downward movement, the atomizer 23 injects fuel which is ignited by the temperature of the compressed air in the chamber 18. The gas exploding mixture will pass the check valve 24 and enter the cylinder 70 2 where it will give an added power impulse to the piston 4 as it travels downwardly. The valve 24 remains open until the piston 4 reaches the bottom of its stroke, because the pressure in the chamber 18 is greater at all 75 times than the pressure in the cylinder 2 during this stroke.

At the end of the power stroke, the valve stem 27 contacts with the disc 28 and opens the valve 26. The escaping exhaust opens 80 the check valve 32 in the exhaust pipe 30. The out-rush of the exhaust gases is aided by the suction device 31.

Returning to the pump piston 5, it will be noted that when the engine piston 4 has moved from the center of its downward stroke to the bottom of its downward stroke, the pump piston 5 moves from slightly below the top of its stroke to the bottom end of its stroke, and in so doing the piston 5 sucks in 90 a new charge of air from the intake manifold 21. On the return upward stroke of the engine piston 4, the piston 5 also starts moving upwardly and reaches the top of its stroke slightly before the piston 4 reaches the midpoint of its stroke.

The compressed air charge formed by the piston 5 will be delivered into the chamber 18 and from there delivered to the top of the cylinder 2 without an injection of fuel being made by the atomizer 23. To pass the compressed air to the top of cylinder 2, the valve plug 33 only of the valve 24 opens, since the pressure of the air alone is not sufficient to overcome the spring 38. In the two-cycle principle engine, the spring 38 presents a greater tension than the spring 35. The compressed air is delivered into the top of the cylinder 2 prior to the piston 4 reaching the top of its stroke.

The engine piston 4 continues on its upward movement from the middle of its stroke to the top and compresses the air charge in the cylinder 2. Simultaneously with this upward movement of the piston 4, the piston 5 moves down to the bottom end of its stroke. All of the valves are closed, and the cycle is ready to be repeated.

Cycle of operations for four-cycle arrangement

95 The cylinder 2 has already been charged with air and the piston 4 is at the top of its stroke. The piston 5 is at the bottom of its stroke. All of the valves are closed. An air charge has also been drawn into the cylinder 3. At this phase of the operation, the atomizer 25 injects a fuel charge which is ignited by the temperature of the compressed air charge, this driving the piston 4 down- 100

wardly. Slightly before the piston 4 has reached the midpoint of its downward movement, the piston 5 will have compressed the air in the cylinder 3 and will have delivered this compressed air into the chamber 18 through the check valve 22.

At the instant the piston 4 reaches the midpoint of its downward movement, the atomizer 23 injects fuel which is ignited by the temperature of the compressed air in the chamber 18. The gas explosion will pass the check valve 24 and enter the cylinder 2, where it will give an added power impulse to the piston 4 as it travels downwardly. The valve 24 remains open until the piston 4 reaches the bottom of its stroke, because the pressure in the chamber 18 is greater at all times than the pressure in the cylinder 2 during this stroke.

At the end of the power stroke, the valve stem 27 contacts with the disc 28 and opens the valve 26. The exhaust gases will escape in the manner already stated.

Returning to the pump piston 5, it will be noted that when the engine piston 4 has moved from the center of its downward stroke to the bottom of its downward stroke, the pump piston 5 moves from slightly below the top of its stroke to the bottom end of its stroke, and in so doing the piston sucks in a new charge of air from the intake manifold 21. On the return upward stroke of the engine piston 4, the pump piston 5 also starts moving upwardly and reaches the top of its stroke slightly before the piston 4 reaches the midpoint of its stroke. The compressed charge formed by the piston 5 will be delivered into the chamber 18 and retained therein, the check valve 24 having a spring 35 that is designed to allow the valve plug 33 to open only after two such compressed charges have been delivered into the chamber 18, or one compressed air charge and an explosion resulting from an injection of fuel.

When the piston 4 has reached the top of its stroke, the piston 5 has moved to the bottom end of its stroke, and in doing so has drawn into the cylinder 3 a fresh charge of air from the intake manifold 21. On its return downward stroke, when the piston 4 has reached the midpoint of that downward stroke, the piston 5 will have reached the top of its stroke and will have compressed the air in the cylinder 3, delivering it into the chamber 18. The check valve 24 still remains closed, its spring 35 being strong enough to permit the plug 33 to open only after two such compressed charges have been delivered into the chamber 18. When the piston 4 has moved from the midpoint of this return downward stroke to the bottom of the stroke, the piston 5 has moved to the bottom of its stroke and has drawn a fresh air charge into the cylinder 3 from the intake manifold 21.

On the succeeding upward stroke of the

piston 4, when it has reached the midpoint of that upward stroke, the piston 5 will have compressed the air in the cylinder 3 delivering it into the chamber 18. There now being more than two compressed charges delivered into the chamber 18, the check valve 24 will open and the compressed air in the chamber 18 will be delivered into the top of the cylinder 2. The compressed air is delivered into the top of cylinder 2 prior to the piston 4 reaching the top of its stroke.

The engine piston 4 continues its upward movement from the middle of its stroke to the top and compresses the air charge in the cylinder 2. Simultaneously with this upward movement of the piston 4, the piston 5 moves down to the bottom end of its stroke. All of the valves are closed, and the cycle is ready to be repeated.

It is thus apparent that the power piston 85 receives two impulses on every other downward stroke, and that I have provided means for supplying fuel and compressed air to the power cylinder, as well as means for exhausting the products of combustion. Although 90 the air is compressed in a separate cylinder, the compressed air is delivered to the power cylinder at the proper instant. Since the operation is analogous to that of a four-cycle engine insofar as I have provided for compressing air and gas, delivering the same to the power cylinder, exploding the charge, and subsequently exhausting the power cylinder. I have used the expression "four-cycle" 95 in the specification, and the same should be 100 interpreted in light of the description.

It will be seen that the only mechanical difference in the four cycle operation and the two cycle operation is the tensile strength allowed for the spring 35 on the valve plug 33. It will also be seen from the above cycle description that in the case of the four cycle operation, the opening at every downward stroke of the piston 4 of the exhaust valve 26 by the contacting of the valve stem 27 with the disc 28 is immaterial. It is to be noted, also, that the phase setting relationship of piston 4 and piston 5 and their relative motions are the same for the four cycle operation and the two cycle operation. The gear 105 wheels 10 and 11 may be made any ratio of sizes relative to each other when the spring 35 on the valve plug 33 is altered in tensile strength so that the valve plug 33 admits the compressed air charge to the cylinder 2 110 during the compression stroke of the piston 4. The firing heads of the engine may be provided with hot bulbs if desired.

It is obvious that any number of cylinders may be used, and these may be arranged 125 straight-in-line, V-type, or radial type. The idler gear 12 may be dispensed with if desired, or more than one idler gear may be employed.

Although I have shown and described one 130

embodiment of my invention, it is to be understood that the same is susceptible of various changes, and I reserve the right to employ such changes as may come within the scope of the claims hereto annexed.

5 I claim:

1. A compression explosion engine comprising a power cylinder, a piston mounted therein, a pump cylinder, a piston mounted therein, connecting rods and gearing operatively connecting the pistons together for causing the pump piston to operate faster than the power piston, a compartment, a check valve controlling the flow of fluid from the pump cylinder into the compartment, a second check valve disposed between the compartment and the power cylinder, an intake for the pump cylinder, an exhaust for the power cylinder, a fuel injector mounted in the compartment, and a second fuel injector arranged in the power cylinder.
- 10 2. A compression explosion engine comprising a power cylinder, a piston mounted therein, a pump cylinder, a piston mounted therein, connecting rods and gearing operatively connecting the pistons together for causing the pump piston to operate faster than the power piston, a compartment, a check valve controlling the flow of fluid from the pump cylinder into the compartment, a compound check valve disposed between the compartment and the power cylinder, an intake for the pump cylinder, an exhaust for the power cylinder, a fuel injector mounted in the compartment, and a second fuel injector arranged in the power cylinder.
- 15 3. A compression explosion engine comprising a power cylinder, a power piston movable therein and with the cylinder defining a compression chamber, an auxiliary compression chamber, a check valve disposed between the two chambers, a pump cylinder, a check valve disposed between the pump cylinder and the auxiliary chamber, a fuel injector mounted in the auxiliary compression chamber, and a second fuel injector arranged in the power cylinder.
- 20 4. In a compression explosion engine, a cylinder, a piston, an exhaust valve carried by the piston, an exhaust pipe, an abutment carried by the pipe for opening the valve when the piston completes its power stroke, and an exhauster for placing a partial vacuum on the exhaust pipe for withdrawing the gases.
- 25 5. A compression explosion engine comprising a power cylinder, a piston mounted therein, a pump cylinder, a piston mounted therein, connecting rods secured to the piston 5 tons, a large gear having the power piston connecting rod radially mounted thereon, a small gear meshing with the large gear and having the pump piston connecting rod radially mounted thereon, an auxiliary compression and explosion chamber placing the

pump cylinder in communication with the power cylinder, check valves controlling the flow of fluid from the pump cylinder to the power cylinder, a fuel injector mounted in the power cylinder and a second fuel injector arranged in the auxiliary chamber.

Signed at Oakland, in the county of Alameda and State of California, this 30th day of June, A. D. 1930.
